UNITED STATES PATENT OFFICE.

LEVON S. SETRAKIAN, OF FRESNO, CALIFORNIA.

WRIST SUPPORT FOR PENMEN.

Application filed June 12, 1923. Serial No. 644,958.

To all whom it may concern:

Be it known that I, LEVON S. SETRAKIAN, a citizen of the United States, residing at Fresno, in the county of Fresno, and State of California, have invented certain new and useful Improvements in Wrist Supports for Penmen, of which the following is a specification.

The object of this invention is to provide a simple and inexpensive device whereby the wrist of a penman will be supported in such position that the free arm movement will be facilitated and fatigue will be overcome. The invention seeks to provide a device which may be readily applied to the wrist of the user and firmly secured without causing any discomfort or inconvenience and which will permit free use of the fingers while supporting the wrist out of contact with the desk or table but in such manner that it may move freely as the writing proceeds. The invention is illustrated in the accompanying drawings and will be hereinafter fully set forth.

25 In the drawings:

Figure 1 is a perspective view showing the application of my device;

Fig. 2 is a bottom plan view of the device removed and in a flat condition;

30 Fig. 3 is a top plan view of the same;

Fig. 4 is a longitudinal section on the line 4—4 of Fig. 2, and

Fig. 5 is a detail section through the movable rest.

35 In carrying out my invention, I employ a band consisting of a ply of leather 1 and a lining 2 of some soft flexible material. The band is of such dimensions as to completely encircle the wrist of the user when applied and upon the outer side of the band adjacent one end thereof I secure a buckle 3 which may be engaged by a strap 4 secured to the opposite end of the band whereby the band may be securely fastened about the wrist. In order that the band may conform to the wrist, I form incisions in the leather ply and then bevel the opposed faces of the incisions, as indicated at 5, so that the said faces may be overlapped, as shown at 6, the overlapped portions being permanently united by lines of stitching, indicated at 7. In the drawings, I have shown three lines of stitching, one line extending along the edge of each overlapped portion and one line extending along the

center of said portions from the edge of the band to the point where the edges of the overlapped portions meet; but it will be understood, of course, that the central line of stitching may be omitted. A line of 60 stitching, indicated at 8, may be run around the entire marginal portion of the band so as to impart a neat ornamental appearance thereto, but, in order to avoid wrinkles or loose portions in the lining, it is desirable 65 to affix the lining to the outer leather ply by an adhesive, as will be readily understood. Adjacent the forward edge of the band and near the center thereof openings are formed through the plies, and in the 70 said openings I secure a base plate 9 having a central annular boss 10 formed thereon, the major portion of the base plate lying within the lining ply, while the boss extends through and terminates flush with 75 the outer surface of the outer ply, as shown most clearly in Fig. 5. The boss and the body of the plate 9 are hollowed out centrally to provide a chamber 11 having a 80 grooved annular wall 12 forming a race-way for small anti-friction balls 13, as will be readily understood. Fitted against the outer side of the outer ply 1 is a cup plate 14 having a central opening 15 therethrough, the wall of which preferably converges out- 85 wardly. A large ball or rolling support 16 is engaged in the central chamber of the boss 10 and extends through the opening 15 of the cup plate, the diameter of the said ball being less than the inner diameter of 90 the said opening 15 and greater than the outer diameter thereof so that, when the device is applied to the wrist, the ball may project through the cup plate but will be prevented from dropping therefrom so that, 95 while a freely moving support is in contact with the table or desk, the cup plate will be held out of contact therewith and frictional resistance to the free movement of the wrist and the hand of the writer will be minimized. The cup plate is held in position by screws 17 inserted through the plate 9 and the ply 1 of the band into the cup plate, as shown and as will be readily 100 understood.

105 In use, the band is secured around the wrist so that the movable support 16 will be disposed at the under side of the wrist and immediately at the base of the hand, as indicated in Fig. 1, the wrist being thus sup- 110

ported out of contact with the desk or table and the hand supported comfortably in a natural position so that it will not exert pressure upon the table, desk or other fixed support, the fingers being left free to grasp the pen or pencil or other scribing implement. By the use of my device, bookkeepers and other persons engaged in occupations which necessitate constant or substantially constant writing will be enabled to write uninterruptedly for considerable periods of time without feeling fatigue in the wrist or in the muscles of the hand and fingers. Moreover, the device serves as a brace for weak wrists so that they are strengthened, and supports the wrist and hand so that the free-arm movement which is essential to fine penmanship will be facilitated. The device could be very advantageously employed also for teaching children and indifferent penmen to write or to improve their handwriting. The device is obviously simple and may be produced at a very low cost, and the strap and buckle employed for securing the band in position adapts a single band for use upon wrists of a variety of sizes. While I have specifically mentioned leather as the material for the outer ply of the band, it will be understood that any durable flexible and wear-resisting material may be employed and the lining may be omitted, although I prefer to employ the same inasmuch as it provides a soft surface for contact with the skin and thereby avoids irritation of tender flesh.

The overlapped construction indicated at 6 causes the band to conform to the wrist and hand and tends to prevent the stiff tir-

ing wrist movement which causes illegibility in the writing. 40

Having thus described the invention, what is claimed as new is:

1. A device for the purpose set forth comprising a flexible band to be secured about the wrist of the user, a raceway secured in 45 the band, a freely movable support engaged in said raceway, and a cup plate secured upon the outer side of the band and retaining said support in engagement with the raceway. 50

2. A device for the purpose set forth consisting of a flexible band to encircle the wrist of the user, means for securing the band in position, a plate secured to the inner side of the band and having a boss projecting therethrough, anti-friction devices within said boss, a cup plate secured upon the outer side of the band over the said boss and having an outwardly tapered opening therethrough, and a freely rotatable support held by and extending through said cup plate and engaging the anti-friction devices fitted in the boss. 55 60

3. A device for the purpose set forth comprising a band consisting of an outer ply of flexible shape-retaining material and an inner ply of cushioning material, the outer ply having incisions formed therein at one edge and having the opposed faces of the incisions oppositely beveled, the said opposed faces being overlapped and permanently secured together, and a freely movable rest fitted in and carried by the said plies and projecting from the outer ply. 65 70

In testimony whereof I affix my signature.
LEVON S. SETRAKIAN. [L. S.]
